US00D680432S

(12) **United States Design Patent**
Geier

(10) **Patent No.:** **US D680,432 S**
(45) **Date of Patent:** **** Apr. 23, 2013**

(54) **SPRAY CAP FOR AEROSOL CANS OR
SIMILAR FLUID CONTAINERS**

(75) Inventor: **Adalberto Geier**, Calceranica al Lago
(IT)

(73) Assignee: **Coster Technologie Speciali S.p.A.**,
Calceranica al Lago (Trento) (IT)

(**) Term: **14 Years**

(21) Appl. No.: **29/423,939**

(22) Filed: **Jun. 6, 2012**

(51) LOC (9) Cl. **09-07**

(52) U.S. Cl.

USPC **D9/448**; D9/453; D9/454

(58) **Field of Classification Search** D9/724,
D9/688, 686, 454, 450, 449, 448, 447, 435,
D9/434; D28/7; 239/333; 222/95, 536,
222/402.1, 153.14, 153.05, 153.04; 220/200;
215/200
